FOLDING BARB FISH GAFF

William S. Blodgett and Leonard R. Blodgett,
Portland, Oreg.

Application May 5, 1937, Serial No. 140,920

6 Claims. (Cl. 43—5)

Our invention relates to a gaff provided with a barb proximate its point which can be caused to recede within the body of the gaff to permit removal of a fish.

5 The object of the invention is to provide a fish gaff having a folding barb which normally rests within the body of the gaff and does not interfere with the gaffing of a fish, but which will open out and effectively prevent the fish 10 from loosening itself from the gaff.

The object of the invention is to provide a gaff with a folding barb which folds into the gaff and means for positively causing the barb to fold, which means may be operated by the 15 hand of a person in which the gaff is being held.

An object of the invention is to embody simple construction and few parts in the manufacture of the gaff in order to reduce manufacturing 20 expenses and to eliminate as far as possible the chances of breakage.

These and other objects of the invention will become more readily apparent upon a study of the following description when read in connection 25 with the accompanying drawing which forms a part thereof.

In the drawing, Figure 1 is a side elevation of the fish gaff which shows it being employed for gaffing a fish.

30 Figure 2 is an enlarged side elevation with portions in section in order to disclose the internal construction of the gaff.

Figure 3 is an enlarged, vertical sectional detail of the point of the gaff. This view shows the 35 construction of the folding barb and the means for folding the barb.

Figure 4 is a plan of a straight type of gaff.

Referring now to the drawing, the numeral 1 indicates the gaff in its entirety, consisting of 40 a shank 2, a hook portion 3 which terminates in a penetrating point 4. The gaff is made of tubular stock, or of solid stock and then bored to provide a longitudinal bore 5 which, of course is closed at point 4. The end of the shank has 45 a larger bore 6 communicating with bore 5, and where these two bores meet there is consequently formed a shoulder or ledge 7 which serves as a spring seat as will presently appear. Carried within the shank and hook portions is 50 a flexible rod 8. On the inside of the hook portion and proximate point 4 is a slot 9 leading into bore 5, and in this slot is seated a barb 10 pivotally mounted on pin 11. Pin 11 has its ends secured in opposite sides of the hook portion, 55 and the pivotal connection of the barb thereto

is within bore 5. Barb 10 has its point 12 slightly curved, outwardly, and this point normally rests upon the exterior portion of the hook forming the rearward end of the slot, as indicated by numeral 13.

Barb 10 has a dog 14 projecting beyond its pivotal connection with pin 11, consequently as the rod 8 is moved lengthwise of the gaff toward point 4 the forward end 15 thereof will engage dog 14 and will move it toward the point 10 10. This will pivot the barb 10 rearwardly until the curved end 12 rests upon the portion 13 of the gaff. The rod is normally out of engagement with the dog, thus allowing it to pivot back and forth. In order to secure this normal disengagement there is provided a spring 16 coiled about the opposite end 17 of rod 8. One end of this spring seats upon shoulder 7 while the opposite end seats upon a sleeve 18 which is solidly secured about rod 8. Hence when the rod is 20 moved forwardly to fold the barb it compresses the spring, and when the rod is released the spring returns it to normal non-engaging position which allows the barb to move out of the slot. In order to hold the sleeve 18 in engagement with the end of spring 16, there is provided a cap 19 which threads on the end of shank 2 holding the sleeve therein. The end of rod 8 projects through the cap and is provided at the end with a button 20. To this button is applied 30 thumb or finger for moving rod 8 against spring 16 in order to fold the barb.

The gaff is mounted on a handle or pole as desired. For this purpose it is provided with a sleeve 21 about the end of the shank. Projecting from this sleeve, radially, is a flat support member 22 provided with fastening holes 23. In order to fasten the gaff to a handle, such handle is provided at its end with a suitable slot to receive the member 22, and holes therethrough 40 corresponding to holes 23. Thereupon fastening members are inserted through the corresponding holes. Figure 1 illustrates a handle 24 so secured to the gaff.

Figure 4 shows a modification of the invention 45 which may be used for spearing fish. This consists of an elongated tubular body 25. In every respect it is similar to gaff 1, with the exception that it does not have sleeve 21, member 22, and hook portion 3. The body 25 may be 50 made as long as is practicable.

In operation gaff 1 is employed as any other gaff, fish being gaffed by inserting point 4 in their flesh. In the event that the fish has a tendency to slip off the gaff, such movement will 55

cause its flesh to engage the outturned end 12 of the barb. This will cause the barb to open out thus effectively preventing the fish slipping off the gaff. It is to be understood that when the 5 fish is gaffed the barb is in closed position, thus it will not tear the flesh. When it is desired to remove the fish from the gaff, the button 20 is pressed, thus moving rod 8 to a position where it closes the barb. Thereafter the fish can be 10 readily removed.

While a specific form of the improvement has been described and illustrated herein, it is desired to be understood that the same may be 15 varied, within the scope of the appended claims, 15 without departing from the spirit of the invention.

Having described our invention, we claim—

1. A gaff, comprising a tubular body having a shank portion and a hook portion terminating 20 in a penetrating point, a slot proximate the point, a barb pivotally mounted within the slot and movable in and out thereof, a flexible rod slid- 25 able back and forth in the shank and hook, a dog projecting from the barb and engageable by one end of the rod and when so engaged piv- 30 otting the barb into the slot, and spring means for maintaining the rod in normal disengagement with the dog.

2. A gaff, comprising a body having a shank 30 portion and a hook portion terminating in a penetrating point, and a slot proximate the point, a barb pivotally mounted to move in and out of the slot and provided with a projecting dog, a member movable back and forth in the shank 35 and hook and when moved in one direction engag- 35 ing the dog and moving the barb into the slot, and spring means for maintaining the mem- ber in normal disengagement with the dog.

3. A gaff, comprising a body having a shank 40 portion and a hook portion terminating in a pene-

trating point and a slot proximate the point, a barb pivotally mounted to move in and out of the slot and provided with a projecting dog at one end and an outwardly curved point at the other end normally resting upon the outer face 5 of the hook portion, a member movable back and forth in the shank and hook and when moved in one direction engaging the dog and moving the barb in the slot to a position wherein the curved end rests upon the face of the hook, and spring 10 means for maintaining the member in normal disengagement with the dog.

4. A gaff, comprising a body having a shank portion and a hook portion with a penetrating point and a slot proximate the point, a barb pivotally mounted to move in and out of the slot and provided with a dog, a member movable back and forth in the shank and hook and when moved in one direction engaging the dog and moving the barb into the slot, and means yieldably main- 15 taining the member in normal disengagement 20 with the dog.

5. A gaff, comprising a body having a shank and a hook portion and a point and a slot proximate the point, a barb pivotally mounted to move 25 in and out of the slot and provided with a dog, a member movable back and forth in the shank and hook and when moved in one direction engag- 30 ing the dog and moving the barb into the slot, means yieldably moving the member in the op- 30 posite direction to disengage the dog, and means for manually moving the member into engagement with the dog.

6. A gaff, comprising a body having a penetrat- 35 ing point and a slot proximate the point, a barb mounted to pivot in and out of the slot, and a normally disengaged member engageable with the barb to move it into the slot.
